UNITED STATES PATENT OFFICE.

DEXTER D. HARDY, OF CHICAGO, ILLINOIS, ASSIGNOR TO THE ILLINOIS HIGH SPEED ENGINE COMPANY, OF SAME PLACE.

STEAM-ENGINE.

SPECIFICATION forming part of Letters Patent No. 331,234, dated November 24, 1885.

Application filed March 27, 1885. Serial No. 160,176. (No model.)

To all whom it may concern:

Be it known that I, DEXTER D. HARDY, a citizen of the United States, residing at Chicago, in the county of Cook and State of Illinois,

have invented certain new and useful Improvements in Steam-Engines, which are fully set forth in the following specification, reference being had to the accompanying drawings, forming a part thereof, in which—

10 Figure 1 is a front elevation of my engine, having the cover and slide-valve removed from one of the steam-chests, so as to show the steam-ports therein. Fig. 2 is a longitudinal section on the line *z z*, Fig. 4. Fig. 3 is a vertical section on the line *y y*, Fig. 1. Fig. 4 is a top view. Fig. 5 is a vertical section of one of the cylinders on the line *s s*, Fig. 2. Fig. 6 is a top view of a modified form of construction of my engine with the top plate removed, 20 and Fig. 7 is a detail elevation showing one form of construction of the valve-rod mechanism.

My invention consists, essentially, in a steam-engine of two or more single-acting cylinders 25 placed equidistant from each other, and preferably in the same plane around a central driving-shaft, each cylinder being offset at or about half the radius of the crank to one side of a line drawn through the center of the 30 driving-shaft and parallel with said cylinder, and each cylinder being provided with a single-acting piston connected by a separate connecting-rod to the same crank on the central driving-shaft, each of said cylinders being also 35 provided with suitable steam and exhaust ports with suitable steam-passages leading therefrom, and having in connection therewith a steam-chest and slide-valve operated by an eccentric on the main shaft, all constructed and arranged as hereinafter more 40 fully set forth.

In the drawings, *A* is the engine-frame, having the cylinders *B B'* attached thereto. Said cylinders are offset or placed, one about half 45 the radius of the crank above and the other the same distance below a line drawn through the center of the driving-shaft *F* and parallel with said cylinders, the object in so offsetting the cylinders being to make the engine more 50 compact and to give it increased power, owing

ing to the less angular thrust of the connecting-rods during their operative stroke than would be the case were the cylinders in a straight line.

M M are steam-chests attached to the cylinders *B B'*. Said engine frame *A*, cylinders *B B'*, and steam-chests *M M* are all cast in one piece.

L is a steam-passage into which the steam from the steam-boiler is admitted through the inlet-opening *i* and conveyed to the steam-chests *M M* through the ports *a a'*.

K is an exhaust-chamber into which the exhaust-ports *J J'* discharge, and *h* is an exhaust-steam pipe leading from the exhaust-chamber.

G G' are single-acting pistons adapted to receive steam at their outer ends, and having the recesses *k k k* for packing-rings. Said pistons are intruncated in form and are attached to the connecting-rods *H H'* by means 70 of the pins *t t'*, said connecting-rods being attached to the same crank *I* of the driving-shaft *F*.

a is the inlet-port from the steam-passage *L* into the steam-chest *M*.

b is the inlet-port from the steam-chest *M* into the cylinder *B*.

V is one of the slide-valves operated by the valve-rod *c*.

ff are rods connecting the arms *e e'*, to which the valve-rods *c c* are attached.

C is an eccentric-rod to operate the valves, being attached at one end to the eccentric *g* on the shaft *F*, and connected to the bar *e'*.

m m are the main bearings in the frame *A*, 85 in which the shaft *F* works, the top halves of which bearings are removable.

o o, *u u*, and *p p* are raised portions of the castings covering the steam-passages.

The engine-frame *A* is cast so as to form 90 with the covers *D D* an inclosed crank-chamber, into which the inner ends of the cylinders *B B'* open, and in which lubricants are placed for lubricating the entire inner working parts of the engine.

In Fig. 2 one of the pistons *G* is shown broken away for the purpose of showing the exhaust-ports *l l*, which would be open on the termination of the stroke of said piston *G*. *J J'* are annular ports, one end of which ter- 100

minate in the exhaust-chamber K, and with which the ports *ll* communicate.

In Fig. 5 a portion of the end of the steam-chest, and also a portion of the raised part of the casting *o*, covering the steam-passage *L*, is shown broken away in order to show the course of the steam from the passage *L* through the port *a* to the steam-chest. Said Fig. 5 also shows the exhaust-passages *ll*, through which the exhaust-steam passes into the annular port *J*, communicating with the exhaust-chamber *K*.

Figs. 6 and 7 illustrate a modified form of construction of my engine wherein the valve mechanism is placed on the inside of the crank-chamber *S*. Instead of the double rods and bars and eccentric and eccentric-rod to operate the valves shown in Fig. 1, the valve-rods *c c* are extended and connect with a yoke, *s*, carrying a sliding block, *x*, in which the eccentric *g* works. The extensions *r r* from the steam-chests to the frame, through which the valve-rods work, are cast with and form a part of the steam chest and frame.

The operation of my engine is as follows: The steam is conveyed by a pipe from the boiler through the inlet-opening *i* to the steam-passage *L*, communicating with both steam-chests *M M* through the ports *aa'*. The port *b* being opened by the movement of the valve, the steam is admitted into the outer end of cylinder *B*, and, acting on the piston *G*, causes it to move inward to the end of its stroke and past the ports *ll*, through which the steam exhausts into the exhaust-chamber *K*. During this movement the force is communicated through the connecting-rod *H* to the crank *I*, carrying it through half of a revolution, and in the meantime carrying the piston *G'* to the position in its cylinder to receive steam. The movement of the valve caused by the action of the eccentric has now closed the inlet-port *b* in the cylinder *B*, and opened the inlet-port into the cylinder *E'*, whence the steam, acting on the piston *G'*, causes it in turn to move inward, carrying the crank through the remaining half of the revolution and the piston *G* back to its point of commencement.

Having fully described my invention, what I claim as new, and desire to secure by Letters Patent, is—

1. In a steam-engine, two single-acting cylinders placed equidistant from each other around a central driving-shaft, each of said cylinders being offset at about one-half of the radius of the crank to one side of a line drawn through the center of the main shaft

and parallel with said cylinder, said cylinders having in connection therewith suitable steam-chests, steam ports and valves, with suitable mechanism for operating the same, and each cylinder having a single-acting piston connected by separate connecting rods to the same crank on the driving-shaft in the manner substantially as and for the uses and purposes specified.

2. In a steam-engine having two or more single-acting cylinders placed around a central driving-shaft and offset to one side of a line drawn through the center of the driving-shaft and parallel to said cylinders, respectively, the combination of the pistons *G G'*, the connecting-rods *H H'*, and the crank *I* on the driving-shaft *F*, working in bearings *m m'*, in the manner and for the purposes specified.

3. In a steam-engine, the engine-frame *A*, having the steam-passage *L* and exhaust-chamber *K* therein, and the cylinders *B B'* on opposite sides of the driving-shaft *F*, and offset, one above and the other below a line drawn through the center of the driving-shaft, and parallel with said cylinders, said cylinders having steam-chests *M M*, attached thereto with steam-ports *a* and *b*, and exhaust-ports *ll* and *J*, in combination with the single-acting pistons *G G'*, provided with the packing-rings *k k*, the connecting-rods *H H'*, attached to the crank *I*, the driving-shaft *F*, working in bearings *m m'* in the frame *A*, and the slide-valves *o o*, in connection with the bars *e e'* and rods *f f*, operated by the eccentric *g* upon the shaft *F*, substantially as and for the uses and purposes specified.

4. In a steam-engine, the engine-frame *A*, having the steam-passage *L* and exhaust-chamber *K'*, therein, the parallel offset-cylinders *B B'*, having the ports *ll* and *J* therein, and the steam-chests *M M*, having the ports *a* and *b* therein, all cast in one piece.

5. In a steam-engine having two cylinders placed at opposite sides of a shaft and offset at opposite sides of a line drawn through said shaft and parallel with said cylinders, the combination of two single-acting valves operated by one eccentric, *g*, or its equivalent, with the driving-shaft *F*, and the two single-acting pistons *G G'*, attached to the same crank *I*, substantially as set forth.

DEXTER D. HARDY.
